BOX FOR POWDERED MATERIALS

Roger H. Casler, Washington, Conn., assignor to Roy S. Sanford & Company, Oxford, Conn., a partnership

Application August 20, 1957, Serial No. 47,458

Term of patent 14 years

(Cl. D58—12)

Fig. 1 is a perspective view of a box for powdered materials showing my new design;

Fig. 2 is an end elevational view thereof;

Fig. 3 is a side elevational view thereof, and

Fig. 4 is a cross sectional view thereof taken on line 4—4 of Fig. 3.

The side and end, not shown, are the same as the side and end shown.

The broken lines in the figures on the drawing are intended to indicate indeterminate length.

I claim:

The ornamental design for a box for powdered materials, substantially as shown and described.
